No. 780,793.

PATENTED JAN. 24, 1905.

P. T. HAHN,
PRINTING DEVICE.
APPLICATION FILED JUNE 30, 1904.

UNITED STATES PATENT OFFICE.

PAUL T. HAHN, OF WOODCLIFF-ON-HUDSON, NEW JERSEY.

PRINTING DEVICE.

SPECIFICATION forming part of Letters Patent No. 780,793, dated January 24, 1905.

Application filed June 30, 1904. Serial No. 214,700.

To all whom it may concern:

Be it known that I, PAUL T. HAHN, a citizen of the United States, residing at Woodcliff-on-Hudson, in the county of Bergen and State 5 of New Jersey, have invented certain new and useful Improvements in Printing Devices, of which the following is a specification, such as will enable those skilled in the art to which it appertains to make and use the same.

- 10 This invention relates to devices or means for printing on wrapping-paper; and the object thereof is to provide an improved device of this class which is designed for use in connection with a roll of wrapping-paper from 15 which strips or sections of paper may be drawn for use in the usual manner, a further object being to provide a device of the class specified for use in retail stores and similar places where wrapping-paper is usually kept 20 in rolls and by means of which any desired advertisement may be printed on separate strips or sections of the paper as they are drawn from and detached from the roll.

The invention is fully disclosed in the following specification, of which the accompanying drawings form a part, in which the separate parts of my improvement are designated by suitable reference characters in each of the views, and in which—

- 30 Figure 1 is a sectional end view of a device or apparatus involving my invention; Fig. 2, a sectional plan view taken on the line 2 2 of Fig. 1; and Fig. 3, a section side view of a detail of the construction, the section being 35 on the line 3 3 of Fig. 2.

In the drawings forming part of this specification I have shown at *a* a roll of ordinary wrapping-paper which is mounted in any suitable support, comprising as shown in the 40 drawings a base *b*, upright side members *b*², and a top member *b*³. The upright side members *b*² are provided with vertical grooves *b*⁴, in which is mounted a vertically-movable head *c*, which normally rests on the roll *a* and the bottom front portion of which is provided 45 with a cutting edge *c*².

Pivoted to the head *c*, near the opposite ends thereof, is a main frame *d*, comprising side arms *d*², connected at the back or rear 50 end thereof by a cross-bar *d*³, and the rear

end portions of the side arms *d*² are much wider than the front end portions thereof, and mounted in said frame, adjacent to the front end portions of the arms *d*² thereof, is a blotter-roller *e*. The side arms *d*² of the 55 main frame *d* are provided with slots *e*², in which are mounted blocks *e*³, which form bearings for the journals *e*⁴ of the blotting-roller *e*, and the outer sides of the arms *d*² of the frame *d* are provided with ears *e*⁵, through 60 which are passed screws *e*⁶, and between the ears *e*⁵ and blocks *e*³ are placed springs *e*⁷, which normally force the blotting-roller *e* in the direction of the roll *a* of paper.

Mounted in the opposite sides of the main 65 frame *d*, rearwardly of and below the blotter-roller *e* is a type-roller *f*, which is of the ordinary spring-roller type and which is provided at one or both ends with a radial pin *f*², which is adapted to strike against a corresponding lug or pin *f*³, secured in one or both of the arms *d*² of the main frame *d* and by means of which the spring type-roller *f* is normally held in the position shown in Fig. 1, and the type on said roller are placed on 75 the top portion thereof, as clearly indicated in Figs. 1 and 2, and said type-roller is provided near its opposite ends with annular beads or collars *f*⁴, which bear on the paper-roll *a* when the type-roller is in position for 80 use.

Within the rear portion of the main frame *d* is pivoted a supplemental frame *g*, composed of side arms *g*² and a rear or back cross-bar *g*³, and the side arms *g*² of the supplemental frame *g* are pivoted over the type-roller *f*, as shown at *g*⁴.

Mounted above the rear portion of the supplemental frame *g* and connected with the main frame *d* is a transversely-arranged ink-holder *h*, the bottom of which is open, and secured in the open bottom of the ink-holder *h* is a pad *h*², of felt or other suitable material, and mounted in the central top portion of the supplemental frame *g* is a main inking-roller *h*³, rearwardly of which is an ink-spreading roller *h*⁴, which is mounted in contact therewith, and below the main inking-roller *h*³ and in contact therewith is a supplemental inking-roller *h*⁵. The rollers *h*³, *h*⁴, and *h*⁵ 95

are all mounted in the supplemental frame, and secured at one or both sides of the main frame is a spring or springs i , which operate in connection with lugs or pins i^2 on the inner 5 sides of the side arms g^2 of the supplemental frame to normally hold the supplemental frame in the position shown in Fig. 1, in which the supplemental inking-roller h^3 is out of contact with the type-roller f .

10 The springs i^1 serve to force the blotting-roller e downwardly and normally hold it in contact with the roll a of wrapping-paper, and said springs also normally serve to hold the main frame d in the position shown in Fig. 15 1, in which the type-roller f is not in contact with the roll a of wrapping-paper.

Connected with the rear or back portion of the supplemental frame g or with the cross-bar g^3 thereof is a handle j , by which said supplemental frame may be depressed, and the downward movement of the supplemental frame g is limited by pins or lugs k , secured to the side arms d^2 of the main frame d , and by applying spring-pressure to the handle j the supplemental frame will be forced downwardly until it strikes the lugs or pins k , and then both the main and supplemental frames may be forced downwardly until the type-roller f strikes the roll a of wrapping-paper.

30 The ink holder or reservoir h is provided with a removable or hinged cover h^3 , having a handle h^4 , and the operation will be readily understood from the foregoing description when taken in connection with the accompanying drawings and the following statement thereof. The end a^2 of the roll a of wrapping-paper normally projects beneath the head c , and whenever it is desired to tear off a piece of this paper the same may be done in the 35 usual manner and without printing thereon, if desired. Whenever it is desired to print an advertisement on the strip of paper torn off, one hand is placed on the handle j of the supplemental frame g , and said frame is depressed 40 until the supplemental inking-roller h is brought in contact with the type-roller f , and both of the frames d and g are then depressed until the type-roller f or the beads or collars f^4 thereon come in contact with the roll a of 45 paper. The end a^2 is then pulled through or beneath the head c , and the desired advertisement is printed on the paper, and said end a^2 is pulled farther through or beneath the head c , and the strip or section of paper with the 50 advertisement thereon is cut off or pulled off in the usual manner.

My invention is in no way limited to the method of or means for connecting the type with the roller f , and such type may be formed 60 on or connected with said roller in any desired manner, and said roller may thus be provided with any preferred form of advertisement.

In the above-described operation of printing an advertisement on the paper as it is 65 drawn from the roll a the type-roller f turns

through approximately a complete revolution, and when pressure is removed from the handle j the various parts of the printing apparatus resume the position shown in Fig. 1, the type-roller f is raised out of contact with the paper-roll a , and the supplemental inking-roller h^3 is raised out of contact with the type-roller f .

In the normal position of the parts shown in Fig. 1 the main inking-roller h^3 is held 75 against the pad h^2 in the bottom of the ink holder or reservoir h ; but when the supplemental frame g is depressed, as hereinbefore described, the connection of the main inking-roller h^3 with the pad h^2 is broken.

The roller h^4 serves to spread the ink on the main inking-roller h^3 , and the supplemental inking-roller h^5 receives the ink from said main inking-roller. The blotting-roller e rests at all times on the paper-roll and serves 85 to dry the ink of the advertisement after the latter has been printed on the paper, as hereinbefore described.

Having fully described my invention, what I claim as new, and desire to secure by Letters 90 Patent, is—

1. In an apparatus of the class described, a frame adapted to receive a roll of paper, a vertically-movable cross-head mounted in said frame and adapted to rest on the roll of paper 95 and provided with a front cutting edge, a main frame pivoted to the rear side of said cross-head, a spring-depressed blotting-roller mounted in said main frame and resting normally on the roll of paper when the latter is in position, a type-roller mounted in the main frame below the blotting-roller and normally held out of contact with the paper-roll, a supplemental frame mounted in the main frame rearwardly of the blotting-roller, an ink-reservoir 100 supported on the main frame above the supplemental frame, means for feeding ink through the bottom of said reservoir, a main inking-roller mounted in the supplemental frame beneath the bottom of the ink-reservoir 105 and normally held in contact therewith, and a supplemental inking-roller mounted in the supplemental frame beneath the main inking-roller and normally held out of contact with the type-roller, said supplemental frame being spring-supported, said supplemental frame being adapted to be depressed in the main frame 110 so as to bring the supplemental inking-roller into contact with the type-roller and both of said frames being adapted to be depressed so as to bring the type-roller into contact with the paper-roll, substantially as shown and described.

2. In an apparatus of the class described, a frame adapted to receive a roll of paper, a vertically-movable cross-head mounted in said frame and adapted to rest on said roll of paper when the latter is in position, a main frame pivoted to one side of said cross-head, a supplemental frame pivoted in the main frame, a 125

spring-depressed blotting-roller mounted in the front portion of the main frame and adapted to normally bear on the paper-roll, the springs which depress the blotting-roller also serving to hold the main frame in a raised position, springs for holding the supplemental frame in a raised position, a type-roller mounted in the main frame rearwardly of the blotting-roller and normally held out of contact with the paper-roll, an ink-reservoir secured in the main frame above the supplemental frame, means for feeding ink through the bottom of the ink-reservoir, inking-rollers mounted in the supplemental frame between the ink-reservoir and the type-roller, said inking-rollers being in contact and one of them being normally held in contact with the bottom of the ink-reservoir and the other normally held out of contact with the type-roller and means whereby the supplemental frame may be depressed in the main frame and both frames depressed, substantially as shown and described.

3. In an apparatus of the class described, a paper-roll holder provided with a vertically-movable cross-head adapted to normally rest on the paper-roll, a vertically-movable main frame pivoted to said cross-head, a supplemental and vertically-movable frame pivoted in the main frame, a blotter-roller mounted in the main frame, a type-roller mounted in the main frame rearwardly of the blotter-roller, an ink-reservoir secured in the main frame above the supplemental frame and inking-rollers mounted in the supplemental frame between the ink-reservoir and the type-roller, substantially as shown and described.

4. In an apparatus of the class described, a paper-roll holder provided with a vertically-movable cross-head adapted to normally rest on the paper-roll, a vertically-movable main frame pivoted to said cross-head, a supplemental and vertically-movable frame pivoted in the main frame, a blotting-roller mounted in the main frame, a type-roller mounted in the main frame rearwardly of the bottom roller, an ink-reservoir secured in the main frame above the supplemental frame, and inking-rollers mounted in the supplemental frame between the ink-reservoir and the type-roller, said supplemental frame being also provided with an ink-spreading roller which bears on one of the inking-rollers, substantially as shown and described.

5. In an apparatus of the class described, a frame adapted to receive a roll of paper and provided with a vertically-movable cross-head adapted to rest on said roll, a main frame pivoted to the cross-head, a blotting-roller mounted in the main frame, a spring-actuated type-roller mounted in the main frame below the

blotting-roller, and means for supplying ink to the type-roller, and springs for supporting the main frame and depressing the blotting-roller, substantially as shown and described.

6. In an apparatus of the class described, a frame adapted to receive a roll of paper, a cross-head mounted in said frame and adapted to bear on the roll of paper, a frame pivoted to said cross-head and provided with a spring-depressed blotting-roller adapted to normally bear on the roll of paper and by which said frame is held in a raised position, a spring-actuated type-roller mounted in the main frame and adapted to bear on a roll of paper when said frame is depressed, means for supplying ink to said type-roller, substantially as shown and described.

7. In an apparatus of the class described, a frame adapted to support a roll of paper, a vertically-movable cross-head mounted therein and adapted to rest on said roll of paper, and a frame pivoted to said cross-head and provided with means for printing an advertisement on said roll of paper, substantially as shown and described.

8. In an apparatus of the class described, a frame provided with a vertically-movable cross-head adapted to rest on a roll of paper mounted in said frame, a frame pivoted to said cross-head, a spring-depressed blotting-roller mounted in said frame and adapted to normally rest on said roll of paper when the latter is in position, the springs which depress said roller also serving to hold said frame in a raised position, a spring-operated type-roller mounted in said frame below the blotting-roller and adapted to be brought in contact with the roll of paper when said frame is depressed and means for supplying ink to the type-roller, substantially as shown and described.

9. In an apparatus of the class described, a frame adapted to support a roll of paper, a vertically-movable cross-head mounted in said frame over the roll of paper, and a rearwardly-extending printing-frame pivoted to said vertically-movable cross-head and adapted to swing in a vertical plane and to be supported by said roll of paper, said printing-frame being provided with means for printing an advertisement on the paper of said roll, substantially as shown and described.

In testimony that I claim the foregoing as my invention I have signed my name, in presence of the subscribing witnesses, this 28th day of June, 1904.

PAUL T. HAHN.
